UNITED STATES PATENT OFFICE

2,530,682

WATER TREATMENT PUMP WITH
MEASURING TRAPVan B. Coldsnow, St. Clair Shores, Mich., assignor
to Dihydrol Company, Detroit, Mich.

Application March 5, 1949, Serial No. 79,887

1 Claim. (Cl. 222—318)

1

This application relates to water treatment systems and discloses a system which includes a unidirectional switch and a unidirectional pump and a solenoid controlled by said switch for actuating said pump, and which is characterized by the provision of a novel metering pump which is constructed to pump a metered amount and only in a predetermined direction, i. e., from the supply of water treatment fluid to the branch line through which flows the water being treated, with the pump arranged for preventing flow from the pump except in the predetermined direction and then only when the water being treated likewise flows in a predetermined direction.

A system constructed in accordance with the foregoing is disclosed in the appended drawings.

In these drawings

Fig. 1 shows the system generally.

Fig. 2 is a section view of the metering pump and actuation means therefor, as if on line 2—2 of Fig. 1.

Fig. 3 is a section view of the metering pump per se, as if on line 3—3 of Fig. 2.

Fig. 4 shows the switch per se.

Fig. 5 is a detailed view of a part of the switch.

Referring to the drawings, it will be seen that Fig. 1 shows a water main or line 10 having a normally closed shut off valve 11 and having a branch 12 containing normally open shut off valves 14 and 15. It is the branch 12 that is equipped with the switch 20, the actuation arrangement 21 and the metering pump 22, now to be described.

In the inlet side of the branch 12 is a conventional water meter 30 whose rotary member 31 is provided with a shaft 32 entering a switch housing 33 whereby normally to rotate clockwise a turntable 34, Fig. 4, having numerous spaced pins 35 for successively engaging a rocker arm 36 pivoted at 37 to a mounting plate 38 and constantly biased clockwise, Fig. 4, by a biasing spring 39. The rocker arm 36 is articulated or "broken," having pivotally mounted thereon, as by a pivot pin 40, a member 41 which is the part engaged by turntable pins 35. Member 41 is connected by a coil spring 42 to a leaf spring arm 43 normally disposed under the zig-zag shaped edge 44 of a rocking plate 45 pivoted at 46 on a post 47 in turn mounted on the stationary plate 38

when tilted closes the circuit between the supply conductors 52 and the conductors 53 leading to the pump actuation means 21, the latter being in the form of a solenoid 54. At 55 is shown a stop for the counterweight 50.

Normally the rotary member 31 of the meter 30 rotates in a manner to rotate the turntable 34 clockwise, Fig. 4, so that pins 35 successively rock the rocker arm 36—41 counterclockwise and successively close the circuit through conductors 52 and 53 and thus successively and repeatedly energize the solenoid 54 for reasons later to be described. However, due to the articulation of the rocker arm 36—41, which is in effect a "broken" arm, reverse rotation of the rotary member 31 of the meter 30 due to reverse flow of water in the branch 12, though causing reverse rotation of the turntable 34, will not cause reverse or clockwise rotation of the rocker arm 36—41 and will not cause repeated tilting of the mercury switch 51 and will not cause repeated circuit closing and energization of the solenoid 54.

Assuming the flow in branch 12 to be in the proper direction, as indicated by the arrows, repeated energization of the solenoid 54 of the actuating means 21 will cause repeated operation of the pump 22 for repeated injections of measured minute quantities of water treatment fluid from the tank 56 into the branch line 12 through the line 57 which connects the pump outlet 60 to the branch line 12.

As a measured minute quantity of water treatment fluid is pumped out through the pump outlet 60 it enters the line 57 and is carried into the branch line 12.

The pump itself, shown in Fig. 3, is disposed in a tank 56 fastened to the lower portion of the branch line 12, as by stirrups 68, and to the vertical leg of the branch line 12, as by a bracket or stirrup 69. The cover 72 of the tank 56 is fastened to the tank itself by screws 73. Cover 72 has a filling spout 74 which is locked by means, not shown.

The pump has a base formed with numerous passageways and orifices, and these have valves and operating parts which will operate in the following manner.

Two vertical pumping shafts 80—81 of the pump are shown in Fig. 3 in their lowermost position, and valve closing balls 82—83—84—85—86 which close the various valves under them are also shown in lowermost or closing position. Shaft 81 pumps fluid from tank 56 into the pump

itself and shaft 80 pumps a metered amount of fluid from the pump to outlet 60.

As the solenoid 54 is energized it rocks a rocker arm 87 clockwise, Fig. 2, on fulcrum 87a to lift a connector or yoke 88 and thus lift the two pump shafts 80-81 with the following results: Pump shaft 81 causes water treatment fluid within the tank 56 to flow upwardly through screened inlet tube 89, past the open valve ball 83, and enter the passage 91 to flow past the open valve ball 85 and enter a spout 92 fastened to a cover 93 of a sight glass 94 on cover 72. Fluid entering the spout 92 from below leaves the spout at its open end 95 to form a pool of a level no higher than as indicated at 96, the level being maintained by an overflow tube 97 connecting the interior of the sight glass 94 and the interior of the tank 56, as shown. The pool 96, however, will empty, not completely, but to an extent determined by the stroke of pump shaft 80, and fluid from pool 96 will be pumped by shaft 80 and descend through passageway 101 and flow through passageway 102-103 past the open valve ball 82 to the passageway 104 then past the open valve ball 84 to passageway 105 past the open valve ball 86 to outlet 60.

Thus, upon each actuation of the solenoid 54 there is injected into the line 57 a minute measured quantity of the water treatment fluid within the tank 56 obtained from the pool 96. At the same time pool 96 is replenished.

It is noted that rocker arm 87 is connected to yoke 88 through a separable and adjustable connection rod 132 which is secured to the yoke 88 by the adjusting nuts 133 and which is detachably connected by a screw pin 134 to the rocker arm. Similarly, rocker arm 87 is detachably and adjustably connected to the solenoid plunger 135 by a pin 136 which may be disposed in any one of several adjusting holes 137 of the plunger 135. These two adjustments are available to vary the stroke of the pumping rods 89 and 81 and thus to vary the amount of fluid being pumped from the tank 53 into the pool 96 and the amount being pumped from that pool 96 to the pump outlet 60.

It is also noted that the return of the rocker arm to the position shown in Fig. 2 is accomplished by means of a spring 140 which constantly biases the rocker arm counter-clockwise and thus opposes the action of the solenoid 54.

It is noted that the pumping of fluid into the pool 96 is adjusted to be greater in amount than the pumping of fluid from that pool to outlet 60. Hence the flow into the pool 96 is always greater than the flow out of that pool and thus there is always maintained a pool 96 which overflows through pipe 97. In this way there is insured sufficient flow out of the pump outlet 60 but not an excess amount, since the amount is determined by the metering action of pump shaft 80 and by the overflow 97. The withdrawal from the pool 96 to outlet 60 is determined by plunger 80 and, hence, the pool 96 is not emptied completely on each stroke, and in this way it is assured that no air is pumped from the reservoir 94 to the outlet 60 but only a metered quantity of fluid forming part of the pool 96. In this way it is insured that the pump cannot become air bound.

It is also noted that the cover 93 of the reservoir 94 is provided with vent holes 150, and that the gap between spout 95 and pool 96 is an air

gap which guarantees that there will be no flow out of the pump in the event of a reduction of pressure on the inlet side of the pump, or at outlet 60, or the establishing of a vacuum on the inlet side of the pump or at outlet 60. In the event of a break in the inlet line 12 and thus a reduction of pressure or a vacuum at the pump outlet 60, there will, nevertheless, be no flow from the tank 56 to the outlet 60 because of the air gap between the spout 95 and the pool 96. In the event of a break in the inlet line only, the amount of liquid in the pool 96 can flow to the outlet 60. There cannot be any flow out of the tank 56 to the pool 96. This operation presupposes the opening of the vents at 150, and it is important that these vents be kept open for, obviously, if these vents are plugged, then no such guarantee can be assured.

In this way there is provided a system which injects minute measured quantities of water treatment fluid into the branch line 12 in response to the rate of flow in the branch line 12 in the proper direction as indicated. The system will not operate in response to reverse flow in the branch line nor will the pump permit a continuing flow to take place from the pump to the pump outlet.

Now having described the system here shown, reference should be had to the claim which follows:

In a pump for pumping fluid from a supply to a water line, a vented reservoir above said supply, means communicating said supply and said reservoir, said communication means terminating in a retroverted downspout at the top of the reservoir and opening downwardly to empty to the lower part of said reservoir, the latter having a discharge opening in its bottom wall, means communicating said discharge opening with said water line, an overflow tube in the lower part of said reservoir having its lower end opening into said supply and its upper open end opening into said reservoir at a point somewhat above the bottom wall of the reservoir, whereby a pool of fluid is maintained in the lower part of said reservoir to a level not above the upper open end of said overflow tube, with such upper open end also being well below the downspout which inlets into said reservoir from said supply to form an air gap between said downspout and said pool and the water line, and means for pumping fluid from said supply through the communication between it and the reservoir and through the downspout to form said pool in said reservoir and for pumping a metered quantity from said pool to said water line through the communication between them.

VAN B. COLDSNOW.
